(57) **CLAIM**

The ornamental design for an ultrasonic surgical console, as shown and described.

DESCRIPTION

FIG. 1 is a top, front right perspective view of an ultrasonic surgical console showing our new design;

FIG. 2 is a top, front left perspective view of the ultrasonic surgical console showing the new design;

FIG. 3 is a bottom, front right perspective view of the ultrasonic surgical console showing the new design;

FIG. 4 is a bottom, front left perspective view of the ultrasonic surgical console showing the new design;

FIG. 5 is a top, rear right perspective view of the ultrasonic surgical console showing the new design;

FIG. 6 is a top, rear left perspective view of the ultrasonic surgical console showing the new design;

FIG. 7 is a bottom, rear right perspective view of the ultrasonic surgical console showing the new design;

FIG. 8 is a bottom, rear left perspective view of the ultrasonic surgical console showing the new design;

FIG. 9 is a left side elevational view of the ultrasonic surgical console showing the new design;

FIG. 10 is a right side elevational view of the ultrasonic surgical console showing the new design;

FIG. 11 is a top plan view of the ultrasonic surgical console showing the new design;

FIG. 12 is a bottom plan view of the ultrasonic surgical console showing the new design;

FIG. 13 is a front elevational view of the ultrasonic surgical console showing the new design;

FIG. 14 is an enlarged view of an opening for a power button taken from the circled section of FIG. 13; and,

FIG. 15 is a rear elevational view of the ultrasonic surgical console showing the new design.

In the drawings, the broken lines show unclaimed portions of the ultrasonic surgical console that form no part of the claimed design. The broken lines on the left and right sides of the design, and the broken line rectangular shape on the

(Continued)

front of the design represent unclaimed surface ornamentation that forms no part of the claimed design.
